Filed Apr. 3, 1968, Ser. No. 11,285

Term of patent 14 years

Int. Cl. D28—03

U.S. Cl. D86—8

FIG. 1 is a front elevational view of a combined brush, comb, and container for hair pins showing my new design, the bristles and the triangular apertures being continuous as indicated by the dash dot lines;

FIG. 2 is a bottom plan view thereof;

FIG. 3 is a side elevational view taken from the left of FIG. 1;

FIG. 4 is a side elevational view taken from the right of FIG. 1; and

FIG. 5 is an enlarged cross-sectional view taken on the line 5—5 of FIG. 1.

I claim:

The ornamental design for a combined brush, comb and container for hair pins, as shown and described.
